DESIGN FOR AN ARTIFICIAL BAIT

Claude V. Mangle, Livermore, Iowa

Application February 7, 1941, Serial No. 98,833

Term of patent 7 years

To all whom it may concern:

Be it known that I, Claude V. Mangle, a citizen of the United States of America, residing at Livermore, in the county of Humboldt and State of Iowa, have invented a new, original, and ornamental Design for an Artificial Bait, of which the following is a specification, reference being had to the accompanying drawing, forming part thereof.

In the drawing—

Figure 1 is a bottom view of an artificial bait, showing my new design;

Figure 2 is a top view of the same; and

Figure 3 is a side elevational view of said artificial bait, as positioned in Figure 2.

I claim:

The ornamental design for an artificial bait, as shown,

CLAUDE V. MANGLE,
